CONTROL UNIT FOR LINECASTING AND COMPOSING MACHINES

Lester M. Walden, Chicago, Ill., assignor to
Teletype Corporation, Chicago, Ill., a corporation of Delaware

Application May 4, 1932, Serial No. 609,073

30 Claims. (Cl. 199—31)

This invention relates to typecasting and composing machines and more particularly to units for the automatic control thereof.

A general object of the present invention is to provide an automatic control unit that may be applied to standard types of linecasting and composing machines and that is especially adaptable to standard keyboard construction, as well as to standard function control in order that the application of an automatic control unit to such machines may be made easily and expeditiously and without need of particular adjustment.

Another object of the present invention is to provide an automatic control unit for linecasting and composing machines in which any irregularities of operation may be compensated for through the operation of intercontrol devices.

Another object of this invention is the provision of a control unit that is responsive to perforations in a control form and that is provided with mechanism adaptable to reconcile to its own operation certain practices in the preparation of such form which are essentially foreign to it.

The present invention comprises improvements that are especially adapted to control unit structures, such as that disclosed in copending application Serial No. 600,606, filed March 23, 1932, wherein is provided a selector mechanism employing a set of specially shaped selectable elements alternately and oppositely cross disposed to a series of selector bars.

As is more completely described in the copending application referred to, this unit is controlled by perforated continuous tape which may be prepared by a special perforating mechanism, such as disclosed in copending application Serial No. 601,172, filed March 25, 1932. This tape, or control form, as it is generally referred to, is progressively fed through a record reader or tape sensing mechanism in which is provided a set of feeler members, adapted upon successive feeding operations to sense the presence or absence of perforations in each transverse row in the control form. A corresponding set of transfer levers conveys each such reading to a set of notched code bars which by a resultant permutative arrangement produces an alignment of notches into which one of a plurality of selectable members is permitted to enter so as to come into operative engagement with a common actuating element.

The motion imparted by the common actuator or striker is preferably so timed as to simulate a manual release stroke such as is usually

imparted by an experienced operator's touch. A constantly rotating cam shaft positioned between opposite alignments of the selectable elements imparts motion to the common striker, spreads the several selectable elements during each operative cycle, and coordinates the several parts of the selecting mechanism with the rest of the control unit.

Preferably, power to operate the control unit is obtained from the linecasting or principal machine by suitable power take-off mechanism and is conveniently distributed to the several movable parts through the medium of a pair of alternatively performing driving gear trains. Since linecasting and composing machines are inherently of complex structure it follows that the possibility of mechanical error in operation is correspondingly great. In contemplation of this characteristic failing several appliances have been embodied into the present invention for the purpose of minimizing the probabilities of occurrence of such errors, and arresting the further operation of the mechanism in the event of interrupted performance. In case the elevator mechanism of the principal machine encounters any obstruction, means have been provided for rendering ineffective further application of operating power, while in case of an obstruction of the manual control handle the latter is designed to yield to such obstruction and to arrest further operation of the control unit.

A more complete understanding of the present invention may be obtained from the following description, taken in conjunction with the accompanying drawings, wherein,

Fig. 1 is a front elevation of a linecasting and composing machine, such as will be generally referred to hereinafter as the principal machine, showing a control unit embodying the present invention installed thereon.

Fig. 2 is a detailed perspective view of the power distributing mechanism located in front of and at the right of the machine as viewed in Fig. 1.

Fig. 3 is a general perspective view of a keyboard mechanism of a principal machine with parts broken away to show the application of the present invention thereon.

Fig. 4 is a detail sectional view, taken approximately on line 4—4 of Fig. 1 illustrating the normal operative position of the selector mechanism during the operation of a yieldable member.

Fig. 5 is a detail sectional view taken on a line similar to that of Fig. 4 but illustrating the effect

of resistance to the operative performance of a yieldable member.

Fig. 6 is a detail sectional view taken approximately on line 6—6 of Fig. 1 illustrating the 5 driving train from the constantly rotating shaft to the elevator raising shaft.

Fig. 7 is a fragmentary detail section similar to Fig. 6 illustrating a condition of operation.

Fig. 8 is a fragmentary detail sectional view 10 similar to Fig. 6 illustrating another condition of operation.

In the detailed description of this machine particular reference is made to the accompanying drawings in which like reference characters 15 indicate similar parts throughout.

Structure

For convenience in applying this unit to standard line-casting and controlling machines its 20 structure is almost entirely supported upon a unitary framework 15 as best indicated in Fig. 1. This framework comprises a base casting 16, the major portion of which underlies the keyboard of the principal machine, while an extended portion 17 is disposed to the right of the machine as viewed in Fig. 1 and carries a power distributing mechanism 18 (Fig. 2), a record reader 19, and the coordinating connection therebetween. A pair of side walls 21 and 22, preferably formed integrally with the base casting 16, are each provided with two bayonet lugs (not shown), the foremost ones of which receive a pair of trunnions which are secured to the keyboard casting, while the rearmost ones rest 35 upon a pair of sleeves through which an elevator raising shaft 23 is supported for rotation.

Power is received by the unit from the principal machine by means of a pulley 24 mounted on the intermediate shaft 25 thereof. As best 40 suggested by Figs. 1, 2 and 6 pulley 24 drives pulley wheel 26 through a pulley belt 27 and imparts a definite and constant rotation to shaft 28 preferably commensurate with the maximum operative speed of the principal machine. 45 A pair of tributary operating shafts 29 and 31 communicate with constantly rotating power shaft 28 through the medium of gear pairs 32 and 33, of which the driven gears 34 and 35 are freely supported upon their respective shafts 29 and 31 and carry secured thereto driving clutch members 36 and 37.

Under control of definite tie-up mechanism each of these driving clutch members is made to impart motion to its respective shaft through 55 the medium of associative driven clutch members 38 and 39, which are preferably of similar construction. Shaft 29 however functions to control the record reading or tape sensing mechanism 19 and the selector mechanism, and will, 60 for convenience, be referred to hereinafter as the record reader power shaft, while shaft 31 functions solely to control the elevator raising mechanism and its associated devices and will be referred to hereinafter as the elevator cam shaft.

Record reader mechanism

A perforated tape 41 is fed through a receiving die 42 of a record reader mechanism, generally indicated 19, in regular intermittent or step-by-step motion, imparted to it by suitable pawl and ratchet feed received from cam 43 by roller engagement 44.

During the rest interval between the aforementioned intermittent motions or steps a set

of feeler levers 45 are permitted to rotate counterclockwise under control of a common bail 46 which engages an alignment of projections 47 integrally formed with each of said levers 45. Bail 46 forms part of a bellcrank structure 48 pivoted on shaft 49 and like the feed mechanism receives its motion from a cam 51 by roller engagement 52, in quite the same manner as the above described mechanism. Feeler levers 45 are of identical structure each having an extended arm 53 terminating in a feeler pin 54, which comprises the immediate sensing medium since it contacts the control form 41 cyclically for the purpose of determining the presence or absence of a perforation therein in its particular longitudinal track. The lowermost portion of feeler levers 45 carry a pair of spaced shoulder abutments 55 and 56 somewhat narrower in over-all dimension than are shoulders 57 and 58 of a set of transfer levers 59 associated individually therewith, so that when any of the shoulders 57 or 58 register opposite their respective abutments 55 or 56, the other of the pair of shoulders clears its respective abutment. Levers 45 are limited in their motion by having 25 provided centrally therewith a hole 61 through the several of which passes a rod 62 of considerably smaller cross-sectional area so as to permit of sufficient clearance therebetween to allow feeler levers 45 during one extremity of motion 30 to have lugs 55 in registration opposite shoulders 57 of their associated transfer levers 59, and during the opposite limit of motion to clear them while the other of the pairs of shoulders 58 come into registration with their associated 35 lugs 56.

Transfer levers 59, in addition to being provided with shoulders 57 and 58, also carry downwardly disposed articulation discs 63 adapted to be received into slots 64 of code bar links 65. 40 the latter members as suggested by their name are connected to a set of code bars 66 and operate to position the latter in accordance with each code combination of perforations in the control tape 41 in the following manner. Shaft 45 67 passing through the several lugs 68 of transfer levers 59 is carried by a suitable bellcrank structure, not shown, and receives a timed reciprocating motion from cam 69 carried upon record reader operating shaft 29 so that when 50 moving upwardly the transfer levers 59 are forced into engagement with their associated feeler levers 45 and depending upon the individual position of each, ultimately determined by the presence or absence of a perforation in the control form 41, these levers 59 receive a corresponding position and by means of their articulation with links 65 impart a corresponding position to the set of code bars 66.

Thus the reading of a transverse row of perforations is first imposed upon the set of feeler levers 45 after which and preferably in successive cycles of operation so as to provide an overlap in operation, the setting is subsequently imposed upon the several code bars 66.

Selector mechanism

In order to concentrate the space in which several selectable elements 71 are confined, code bars 66 are provided with notches 72 upon both 70 edges thereof, and the selectable elements 71 are alternately and oppositely disposed to be accommodated by both sets of said notches 72. As will be seen best in Figs. 4 and 5, the selectable elements 71 are generally of similar con- 75

tour except that in accordance with their respective alignments they are symmetrically opposite. Both aligned rows of elements 71 are pivoted about a common shaft 73 and are urged rearwardly and toward each other by spring elements 74 individual to each selectable element 71. Thus it will be seen from a sectional view such as Fig. 4 that the associated alignments of selectable elements give the appearance of so many pairs of scissors having interposed between their extended portions 75 the set of code bars 66 and a common spreader cam 76.

During each complete rotation of the spreader cam 76 its apices 77 spread selectable elements 71 and also permit them to approach each other two times. However, during each cycle of operation of the apparatus the spreader cam 76 rotates 180° or one-half revolution, its normal rest position being that wherein its apices are in a vertical line, as shown in Fig. 3. For each position of the several code bars 66 a particular one of the plurality of selectable elements 71, which may be either an upper or a lower one, is offered an alignment of notches 72 into which it is permitted to move when, during the following rotation, the spreader cam shaft 76 comes substantially into the position as indicated in Fig. 4, whereupon the several elements 71 are thrust against the set of code bars 66. In order to permit an abrupt descent on the part of selected elements 71 upon the occurrence of such an alignment of notches, cut away portions 78 are provided therein while apices 77 of spreader cam shaft 76 are shouldered sharply on their descending side. In operation, as soon as a particular element 71 is selected; that is, as soon as the code bars 66 come into a particular arrangement to afford a definite alignment of code notches 72, a selected element 71 is permitted to drop quickly into this alignment of notches by virtue of the clearance that is suddenly afforded by the cut away portions 78 in cooperation with apices 77. In contrast, it will be noted that without this the descent of a selected element would depend solely upon the speed of rotation of shaft 76.

Immediately following the selective position of an element 71, common actuator 79 receives a leftward motion (Figs. 4 and 5) through suitable cam engagement (not shown) with shaft 76, and in turn imparts this motion to the selected element 71 by engaging its shoulder portion 81, Fig. 3. Under normal conditions of operation the forward movement of an element 71 originating from the common actuator 79 and acting against spring 80 causes the rotation of its associated bellcrank 82 about pivot 83 by striking its depending arm 84, while the other arm 85 of bellcrank 82 engages an offset portion 86 of a corresponding one of a plurality of key levers 87, as shown in Fig. 4. These levers 87, as more completely described in the copending application referred to, are articulated to individual weights 88 which in turn are associated with timed release mechanisms and operate in a well known manner to release matrices individually from the magazine 89, Fig. 1.

The response on the part of the principal machine subsequent to this point of operation is believed to be too well known to require detailed description herein, it being deemed sufficient to take up those phases of the operation where this particular invention is concerned.

The matrices released from the magazine 89

as above described are received and accumulated upon an assembling block 91 which constitutes part of a conveying mechanism commonly known as the assembling elevator 92. When a sufficient number of matrices are assembled upon block 91 to constitute a full-measure line an elevator signal is received by the record reader mechanism 19 which operates in the following manner.

Elevator mechanism

5

10

In response to the elevator signal code bars 66 are positioned to cause the selection of an element 93 (Figs. 2 and 3) which is of similar configuration to elements 71 with the exception of being provided with an extension 94 and a dependent lug 95, the latter of which upon its movement forward under impetus of the common actuator engages one arm 96 of a T-lever 97, rotating the latter counterclockwise and against the action of its spring 98. The foremost arm 99 of the lever 97, as viewed in Fig. 2, is pivotally connected to a latch bar 101 which terminates in an offset portion 102 adapted to cooperate with a spring urged latch 103, whereby, upon the rotation of lever 97 as just described, latch bar 101 is moved rightwardly until its offset portion 102 passes over shoulder 104 of latch 103 whereupon the latter, under influence of its spring (not shown) rises to prevent the return of bar 101 and its associated T-lever 97. Meanwhile, the other arm 105 of T-lever 97 which is pivotally connected through a link 106 with a clutch disengagement lever 107 moves leftwardly causing the presentation of lever 107 25 in its effective position to receive a lug 108 carried by the driven member 38 of clutch 109. Lug 108 is provided with a beveled surface at its forward portion which during the presentation aforementioned is received into opening 40 30 35 40 45 50 55 60 65 70 75 80 85 90 95 100 105 110 115 120 scribed disengagement lever 107. The mid-portion of floating lever 113 upon engaging arm 117 of bellcrank 118 rotates the latter counterclockwise sufficiently to move shoulder 119 clear of 5 disengagement lever 121 after which the latter in response to a spring (not shown) moves out of effective position and permits the reengagement of driven member 39 with driving member 37.

- 10 The rightward movement of bar 115 through its articulation 112 with floating lever 113 is not in itself sufficient to effect the rotation of bellcrank 118 as described, however, when in addition to this movement the opposite end 123 15 of floating lever 113 is also moved rightwardly, this condition is attained. The opposite end of bar 115 is connected to a lever 124, Fig. 1 which is pivoted at 125 and carries at its free end a follower roller 126 20 adapted to lie in the path of delivery slide arm 127 of the principal machine. Thus it will be understood that when the delivery slide arm 127 is in its normal position as indicated in Fig. 1 bar 115 through the medium of lever 124 25 is maintained in its extreme rightward position, Fig. 2, while at any other time when arm 127 is not in its normal position such as is the case during operation of the elevator 62 bar 115 is in its leftward position into which it moves 30 under the influence of a spring 128. The feature of this structure is that upon the reception of an elevator signal in the record reader the elevator mechanism is not actuated unless the delivery slide arm has returned from its 35 previous operation, resulting thereby in regularity of operation and response on the part of the conveying mechanism of the principal machine.

40 *Elevator signal interceptor*

The proper assembling of matrices and the control of line justification is dependent upon the control tape having been correctly prepared; 45 that is, that a proper number of matrix signals intervene successive elevator signals. In the event, however, that too few signals intervene 50 a pair of elevator signals or in the event of consecutive elevator signals, mechanism is provided for causing nevertheless a desirable response on the part of the principal machine.

Consecutive elevator signals are not always the result of error in the preparation of the tape; for example, in the control of certain 55 automatic devices a pair of consecutive elevator signals are used for effectuating certain special responses on the part of those devices. Except for this practice the control tapes of those certain devices are similar to those adapted to control the present device and may accordingly also be used for the control thereof. The improvement about to be described functions to adapt to the use of the present invention control forms that are primarily intended for use with other devices in which there is employed the aforementioned practice which is essentially foreign to the present case.

70 Referring now to Figs. 1 and 3, attention is directed to the assembling slide bar 129 of the principal machine. This bar carries at its extreme left a vertical portion 131, which as the matrices are received between it and the assembling star wheel (not shown), moves leftwardly carrying with it bar 129. The right end of bar 129 during its normal position and when an in-

sufficient number of matrices have been assembled abuts against one arm 132 of bellcrank member 133 the other arm of which is connected through link 134 as best indicated in Fig. 3 to a cradle structure 135 journalled on shaft 136. An upstanding arm 137 forming part of cradle 135 is disposed during its normal position to overlie extended portion 94 of elevator selectable element or bar 93 to prevent the selection of bar 93, except under certain conditions.

10 Until enough matrices are assembled on the block 91 to move slide bar 129 clear of the bellcrank lever arm 132 for permitting spring 138 to rotate it counterclockwise and to rock the arm 137 out of blocking position, the interposition 15 by the latter in the path of the extended portion 94 prevents the selection of elevator selector bar 93 even though the proper signal is received and an alignment of notches 72 are disposed to permit it to drop into selected position.

20 *Elevator control mechanism*

As is best illustrated in Figs. 1 and 3, the assembling elevator of the principal machine, which operates to deliver an accumulated line of matrices to the delivery slide trackway, is located at the left of the machine and is connected through the medium of link 139 to a lifting arm 141 secured to the elevator operating shaft 25 30 23 which extends horizontally across the foremost portion of the keyboard. The right end of shaft 23 immediately after passing through the adjacent supporting sleeve carries secured to it a manual control lever 142 indicated in Figs. 2, 6 to 8. Adjacent to lever 142 and freely carried on shaft 23 is a roller arm 143 terminating with a cam roller 144 adapted to engage the peripheral surface of a cam 145 carried upon elevator cam shaft 31. Preferably formed integrally with arm 143 and angularly disposed thereto is a sleeve formation 146 in which is carried button 147 and spring 148. In its normal position button 147, urged by spring 148 40 45 engages with its V-shaped nose 149 a cooperating notch 151 in a segmental member 152 which is also securely mounted upon elevator shaft 23.

The normal position of the elevator cam shaft 31, the elevator shaft 23, and operating mechanism is as indicated in Fig. 6, and upon being 50 set in motion by the engagement of clutch 122, elevator cam shaft 31 describes a complete revolution and comes to a stop under control of single revolution clutch mechanism fully described in copending application Serial No. 690,606 referred to above. When cam 145 has raised the elevator mechanism to its extreme limit of motion the several parts assume positions as indicated in Fig. 8 provided, however, that no resistance is encountered nor any impediment is 60 introduced to the freedom of movement of the elevator. When the elevator is not free to move which condition may be established by any of several causes, cam shaft 31 performs its usual cycle of operation placing cam 145 in the position indicated in Fig. 8 during the operative cycle thereof, but since the elevator shaft resists the motion thus imparted to it the operative connection is made ineffective by button 147 which then rises out of its seat 151 and continues up into its arcuate trackway 153. This position (Fig. 7) once having been established the several parts remain thereof until they are manually restored by an operator, who 75

Operation

remedies the cause which interrupted the movement of the elevator.

Arm 143 in addition to carrying follower roller 144 also carries a finger 154 secured to it as indicated in Figs 2 and 7. During the operation of the record reader and while the elevator is at rest finger 154 is in its normal position overlying and engaging projection 155 of a cradle 156. A sidewardly extending arm 157 integrally formed with cradle 156 is disposed during this normal position to just clear the extremity of disengagement lever 107. As soon, however, as arm 143 is started into oscillation by elevator cam 145 finger 154 rises sufficiently to permit cradle 156 in response to its spring 158 to present arm 157 into effectual position for blocking the withdrawal of disengagement lever 107. Cradle 156 is in its effective or blocking position at all times except during the operation of the elevator mechanism or when, pursuant to an elevator operating signal, the consummate movement of the elevator has been impaired by some irregularity or interference.

Since the disengagement lever 107 is maintained in its effectual position by two separate mechanisms; namely, cradle 156 and T-lever latch bar 101 and latch 103 it will be understood that the release of clutch 109 and the consequent starting into rotation of record reader shaft 29 are dependent upon two precedent conditions. A more comprehensive understanding of the complete performance of these two control mechanisms will be had during the course of the complete description of operation following hereinafter.

Manual control handle 142 being securely fixed to elevator shaft 23 normally extends in a horizontal position as indicated in Fig. 6, above the general range in which an operator seated before the machine might locate his knee. In order, therefore, to prevent any injury to the operator such as might otherwise occur, the two members 142 and 143 are maintained as separately operative elements on shaft 23 as best indicated in Fig. 2. Under this condition, if an elevator signal is received and arm 143 started into motion, so far as the frictional engagement between button 147 and segment 152 is concerned, any blocking of the handle 142 operates in the same manner as any other interruption of the elevator mechanism, rendering the driving power ineffectual by causing the button 147 to ride up into the arcuate trackway 153.

A lug 159 formed integrally with arm 143 normally overlies a pin projection 161 carried by one arm of a finger lever 162 pivoted at 163 on handle 142, the other arm of which is provided with a conveniently disposed thumb piece 164. When, in the event of any interference with the movement of handle 142 such as just described, the frictional connection including button 147 is temporarily suspended, the motion imparted to projection 159, by reason of the movement of arm 143 is received through pin 161 to effect a positioning of finger lever 162 as indicated in Fig. 7. Elevator cam shaft 31, after this occurrence, continues its rotation until it has completed its cycle although arm 143 remains in the position as shown in Fig. 7. After removing the object which blocked the movement of handle 142 an operator depresses thumb piece 164 in order to restore arm 143 and its integral member to normalcy through the means of pin 161 and lug 159.

In the operation of the present device a tape 41 which has been previously prepared, as explained above, is inserted into the receiving die 42, as indicated in Fig. 2, and the mechanism started in motion. Tape 41 is then intermittently stepped forward by a pawl and ratchet feed mechanism and continues in this motion until the occurrence of a special group of perforations 10 in the tape to be hereinafter identified as an elevator signal, whereupon it is brought to rest as will be explained. During the short interval of rest between its successive step-by-step motion the set of feeler levers 45 rotate counter-clockwise, when permitted to do so by the presence of a perforation opposite their respective pins 54. Of the several levers 45 those whose pins 54 do encounter perforations are permitted to continue in counterclockwise motion until their lugs 56 come into registration with shoulders 58 of transfer levers 59 at which time the opposite shoulders 57 clear their associated lugs 55; while those levers 45 whose pins 54 do not encounter such perforations but are blocked in position substantially as shown, register their lugs 55 opposite shoulders 57 while their companion lugs 56 clear shoulders 58. Following each setting, the several transfer levers 59 being carried by a bellcrank structure of which shaft 67 forms a part, are moved upwardly forcing those shoulders 57 and 58 into registration with their respective lugs 55 or 56 to engage the latter to serve as fulcrums to effect, upon further elevation of the transfer levers, the rotation of the transfer levers, which rotation, in turn, effects through connection 63 and 64, the right or left movement of code bar links 65, and hence code bars 66.

When a particular code combination that has been imposed upon feeler levers 45 is transferred to the several transfer levers 59, cam 51 acting upon roller 52 rotates bellcrank structure 48 and causes the engagement by shaft 46 of the several feeler lever projections 47 returning them to their extreme clockwise position after which they are again released, in the next cycle of operation, to sense a new code combination. The reception of the new code combination by the transfer levers 59 simultaneously effects a corresponding positioning of the permutation bars 66 following which spreader cam 76 assumes a position similar to that indicated in Fig. 4 permitting the particular selectable element 71, under which there has been presented an alignment of notches 72, to descend or ascend, as the case may be, to a position such as for example the one indicated in Fig. 4. At this instant, striker bar 79 moves leftwardly rotating or dislodging its corresponding yieldable bellcrank lever 82 through the interposition of the element 71.

Where the particular code combination represents a letter or figure this selection causes the release of a corresponding matrix, but where, however, the particular code combination represents a special function, such as, for example, the initiation of operation of the elevator mechanism such a signal is responded to as follows. The performance on the part of the record reader mechanism and its cooperating parts is similar to that just described up to the point of selection of a particular selector bar whereat instead of selecting a matrix releasing bar there is instead selected the special elevator bar 93. On being moved forward this elevator bar rotates

T-lever 97 counterclockwise as viewed in Fig. 2, effecting the latching of bar 101 behind latch member 103 and presenting disengagement lever 107 in effective position for arresting the rotation 5 of record reader shaft 29. Attention is directed to this means as the first of two separate mechanisms that operate to maintain the record reader shaft 29 in dormant condition, the other of the two means being the spring tensioned cradle 10 156 structurally described above.

The rightward movement of latch bar 101 to which is articulated one end of floating lever 113, usually operates to disengage bellcrank lever 118 from lever 121 and allow the elevator cam shaft 31 to be driven through clutch 122, and only in the event that the delivery slide arm 127 has failed to return will this movement on the part of latch bar 101 not be followed by the aforementioned release operation. Where, however, the delivery slide arm 127 or the assembling elevator 92 is interrupted in its movement the foremost end 123 of floating lever 113 will be retained in its extreme leftward position through failure of the delivery slide arm from engaging lever 124 as described above.

Elevator cam shaft 31 makes but one revolution in response to each initiating signal after which it automatically is brought to rest irrespective of the performance on the part of any of the rest of the control mechanism; that is to say, that even though the floating lever 113 should engage bellcrank 118 for longer than normal duration, clutch 122 will operate but once and shaft 31 makes but a single revolution. The single revolution clutch mechanism operates as follows.

Upon being released elevator cam shaft 31 begins its cycle of rotation. A bellcrank not shown in the present disclosure, but more clearly explained in the referred to copending application operates immediately to present disengagement lever 121 back into its effective position so that the next time that the revolving lug of clutch driven member 39 is brought into registration with the opening of lever 121 it is again cammed away as described in connection with clutch 109.

Cam 120 carried by shaft 31 engages an extended portion 110 of latch 103 depressing it sufficiently to permit the offset portion 102 of bar 101 to override shoulder 104 thereof in response to the urge of T-lever spring 98 returning T-lever 97 and its articulated members to normal position. While it would appear that this clockwise return movement on the part of T-lever 97 by shifting link 106 rightwardly would withdraw disengagement lever 107 from its effective position it will be recalled that a secondary blocking means; namely, cradle 156 and its side-wardly extending arm 157, are at this time presented to block the return movement on the part of lever 107 thereby preventing the reengagement of driven clutch member 38 with driving member 35 until the elevator mechanism is completely restored. The proper restoration of the elevator mechanism is manifest by the return movement of roller arm 143 and the reengagement of extension 155 of cradle 156 by finger 154 as described above.

70 Where the elevator mechanism is not permitted to return for any reason or where its interruption has operated to cause the disengagement of friction button 147 with its associated segment 152 finger 154 will fail to return to its normal position and consequently will not

engage the extended portion 155 of cradle 156 to permit the reengagement of power to record reader shaft 29. After the operative connection between button 147 and segment 152 has thus yielded to the interruption of movement of the elevator 92, or through a blocking of movement of the manual control lever 142 further operation of the unit is suspended until the cause of such interruption is remedied and finger 154 restored to its normal position by depressing 10 thumb lever 162 as previously described.

Where as in the case just described one elevator signal has been received and in response thereto the elevator mechanism has been operated and thereafter another elevator signal is received before any matrices are assembled, or before a sufficient number of them are assembled, delivery slide 129 will not have been moved leftwardly, (Figs. 1 and 3) far enough to completely disengage arm 132 of bellcrank 133. For this reason link 134 to which bellcrank 133 is connected remains down as shown in Fig. 3 and maintains cradle 135 in its extreme clockwise position whereas arm 137 is disposed to overlie extension 94 of elevator selector bar 93. 25

When, therefore, the second elevator signal is received, as mentioned, although the code bars 66 present to the elevator selector bar 93 an alignment of notches 72 into which it may descent yet it cannot do so because of the aforementioned blocking of extension 94 by arm 131. Instead of affecting the elevator operating mechanism, therefore, the second signal is ineffective, and the assembling operation allowed to continue as though there had been no such second elevator signal. 35

While the present disclosure is made with reference to a particular structure it is to be understood that numerous modifications and variations may be made without departing from the spirit and scope of the present invention. It is therefore not intended to be limited by any of the specific illustrations in the accompanying drawings nor to the particular language used in the foregoing specification but to be permitted a construction of the following claims.

What is claimed is:

1. In a linecasting and composing machine, a composing mechanism, a periodically operative mechanism, a record reader, a selectable 50 element operated by said record reader in response to certain signals for actuating said periodically operative mechanism, and means responsive to a predetermined condition for preventing the selection of said selectable element. 55

2. In a linecasting machine, a plurality of key-levers, an automatic control mechanism for actuating said keylevers including a corresponding plurality of selectable elements, a corresponding plurality of members intermediate said keylevers and said elements, means operative upon the selection of each of said elements by said control mechanism to cause the actuation of its corresponding keylever through the medium of its intermediate member, and yieldable means associated with said intermediate members operative to absorb the motion imparted by said selectable elements when it is resisted by said keylevers.

3. In a composing machine, a plurality of keylevers, a plurality of yieldable actuators for operating said keylevers, and an automatic control unit including a record reader, and a plurality of selectable elements each operative upon 75

its selection by said unit to impart motion to a corresponding one of said actuators.

4. In a linecasting machine, a composing mechanism and a casting mechanism, an automatic control mechanism including a plurality of individually selectable elements, a record reader for selecting each of said elements, a conveyor operative between said composing and said casting mechanisms, one of said selectable elements being operative to actuate said conveyor, and means under control of said composing mechanism to prevent the selection of said one of said selectable elements.

5. In an automatic mechanism for keyboard control, a plurality of keylevers to be manually operated, a plurality of elements individually and automatically selectable, a plurality of yieldable members each intermediate said keylevers and said elements, and a common actuator intermittently operated to impart motion through selected ones of said elements to their corresponding intermediate members and keylevers.

6. An automatic control unit for linecasting and composing machines including a plurality of manually operable keylevers, a plurality of individually and automatically selectable actuators, and a plurality of pivoted intermediate members receiving motion from said actuators to be imparted to said keylevers and displaceably yieldable in the event of undue resistance to motion by said keylevers.

7. In an automatic control unit for manually operable keyboards, actuating mechanism for approximating manual technique comprising a plurality of fingers operative upon a keyboard, a common impeller, mechanism for imparting to said impeller abrupt reciprocative motion, a plurality of interposition members individually selectable into position for communicating motion from said impeller to one of said fingers, and a yieldable agency individual to each finger for absorbing excessive or resisted motion.

8. In a linecasting machine, a composing mechanism, a conveyor means for operating said conveyor including a handle for manual control, and a power driven train for automatic control, and a frictional driving connection within said operating means subordinating said power driven train and rendered ineffective in the event of predetermined conditions.

9. In a linecasting and composing machine, an elevator, mechanism for operating said elevator, including a manual manipulator and a power driven means, characterized by means for rendering the driving connection between said power driven means and said mechanism ineffective including a spring pressed detent, and a segment having a trackway within which said detent is received in the event of any impediment in the operation of said elevator.

10. In a linecasting and composing machine, a plurality of matrix releasing elements, mechanism responsive to perforations in a tape for controlling the operation of the matrix releasing elements, an elevator into which the released matrices are assembled, a cam for moving said elevator, a clutch through which power is communicated to said cam, in combination with a member movable with said elevator, and a spring actuated means cooperating with said member and said cam but effective under predetermined conditions for disabling the application of further power to said elevator.

11. In a linecasting and composing machine, a periodically operative apparatus, a source of

5 motive power for operating said apparatus, a signal controlled means for automatically engaging said source to said apparatus a disabling means associated with said apparatus comprising a connecting element yieldable in a direction transverse to the operating line of force upon encountering a predetermined amount of resistance to motion, and a spring-urged detent connecting said disabling means and said apparatus including bevel engagement therebetween adapted to be overcome by predetermined resisting force.

10 12. In a linecasting machine, a conveying mechanism, and a signal responsive unit for automatically controlling said machine and said mechanism comprising a cyclically operative power cam shaft for actuating said mechanism, in combination with a driving connection between said shaft and said mechanism comprising a spring-urged detent yieldable in a direction transverse to that in which the driving power is communicated.

15 13. In a linecasting machine, a power take-off mechanism for actuating a periodically operative organ comprising a continuously rotating shaft, a periodically rotatable shaft tributary to said continuously rotating shaft, a clutch for effecting the operative connection between said shafts, and single revolution release mechanism controlling said clutch, in combination with a limited resistance connection between said periodic shaft and the organ to which it is connected comprising a detent having notched engagement within said clutch.

20 14. In a linecasting machine, a conveyor mechanism including an automatic control unit therefor, a power driven train for operating said mechanism, and a handle for manually controlling said mechanism through which said power train is also operative, in combination with means associated with said handle collapsible under predetermined conditions for rendering ineffective the operative connection therethrough.

25 15. A linecasting machine including a periodically operative mechanism and a constantly operative mechanism, an automatic control unit for both mechanisms, a common source of power for both mechanisms, a manually operative means for actuating said periodic mechanism, and means under control of said unit for automatically operating said periodic mechanism through said manually operative means, in combination with buffer apparatus within said manual means operative to absorb resisted motion.

30 16. In a selector device, a plurality of parallelly disposed selectable bars, a set of code bars variously positionable to afford a selective clearance to each of said selectable bars individually, a mechanism operatively controlled by the movement of one of said selectable bars into its selective clearance, and means controlled by a predetermined condition of said mechanism to prevent the selection of said one of said bars during the presentment of its selective clearance.

35 17. In a linecasting and composing machine, a periodically operative mechanism, a plurality of selectable elements one of which controls said mechanism, a set of code bars positionable to present a selective clearance to said one of said elements, and a blocking member responsive to a condition of said mechanism for preventing the movement of said one of said elements into its selective clearance.

40 18. In a linecasting and composing machine,

- a periodically operative conveyor and a control mechanism for automatically initiating and operating said conveyor including a constantly rotating shaft, a periodically rotatable shaft, a 5 single revolution clutch engagement between said shafts, and driving connection between said periodically rotatable shaft and said conveyor in combination with a detent mechanism for disengaging operative connection thereto upon predetermined conditions. 10
19. In a linecomposing machine, a manual control board including a plurality of aligned function controlling means, an automatic control unit including a corresponding plurality of 15 individually selectable actuators for manipulating said means, a set of actuator selectors permutatively positionable in accordance with control signals, and a signal controlled mechanism for conditioning each of said actuator 20 selectors in accordance with received signals, in combination with means controlled by certain functions of said machine for preventing the selection of an actuator in response to its selecting signal. 25
20. In a linecasting machine, a matrix assembling carriage, means for gauging the accumulation of matrices in said carriage, an elevator for lifting said carriage, and a signal responsive selector mechanism including an element 30 selectable for operating said elevator, in combination with means conditioned by said gauging means for preventing the selection of said element. 35
21. In a linecasting machine, a plurality of keylevers, matrix release elements controlled by said keylevers, and an automatic control mechanism for actuating said keylevers in response to predetermined conditions characterized by a yieldable connection between said controlled 40 mechanism and said keylevers for absorbing resistance to movement on the part of said keylevers. 45
22. The combination set forth in claim 21 in which said yieldable connection comprises bell-crank levers intermediate said keylevers and said automatic controlled mechanism, and spring loaded seating means displaceable for absorbing resistance from said keylevers. 50
23. In a linecasting and composing machine, a plurality of matrix releasing members, an element individual to each of said members for controlling their operation, a set of notched 55 selectors capable of permutative placement for individually selecting each of said elements, a periodically operated mechanism including a carriage for receiving the matrices, and an element operated in response to a certain signal for initiating the operation of said mechanism, in combination with means operative directly 60 and mechanically on said last mentioned element for preventing its performance under predetermined conditions. 65
24. In a composing machine, a keyboard control mechanism including a plurality of keylevers for manually releasing matrices, and an automatic unit responsive to start signals for selectively actuating said keyboard, in combination with yieldable elements for communicating the 70 selective actuation to said keylevers at foremost portions thereof so as to avoid obstructing accessibility for manual control. 75
25. In a linecasting and composing machine, an automatic control unit including a periodically operating power shaft, a device associated 5 with said machine to be operated by said shaft, means carried by said shaft for manually actuating said device, and a connection between said shaft and said device including a yieldable intermediary effective to maintain operative connection below predetermined limits of resistance to the movement of said device and responsive to excessive resistance thereto by disabling its operative connection while permitting said shaft to continue in motion. 10
26. In a linecasting and composing machine, an elevator for raising assembled matrices from a composing level to a higher level, a rock shaft through which power is to be communicated for moving said elevator, said shaft describing an angular rotation from a zero position through a definite arc, an automatic control mechanism, an element carried by said shaft effective during the zero position thereof to initiate the performance of said mechanism, and means for permitting the altered relationship of said element and said shaft for suspending the performance of said mechanism. 15
27. In a linecasting and composing machine, a periodically operative organ and a regularly operative organ, a rock shaft through which power is communicated for actuating said periodically operative organ, a rotatable shaft through which power is communicated for actuating said regularly operative organ, an element 20 carried by said rock shaft and effective during the zero position of said rock shaft to initiate the performance of said rotatable shaft, and means for absorbing the motion communicated from said rotatable shaft by altering the normal relationship of said element and said rock shaft. 25
28. In a linecasting and composing machine, a periodically operative organ and a regularly operative organ, intercontrol means effective 30 during the initiation into operation of said periodically operative organ for arresting the operation of said regularly operative organ, a shaft rotatable for actuating said periodically operative organ, a detented arm having a normal angular position with respect to said shaft, an element carried by said arm and effective during the zero position of said shaft to initiate into operation said regularly operative organ, and means for altering the angular relationship 35 of said element and said shaft for thereby disabling said element. 40
29. In a permutation selector mechanism, a set of code bars in parallel alignment, a plurality of selectable bars in transverse parallel alignment, means for selectively positioning said code bars and for thereby conditioning one of said plurality of selector bars, an actuator for imparting a function performing motion to said selector bars upon their being selectively conditioned individually, and means associated with each of said selector bars for transmitting said motion to an objective device including a spring seated member adapted to be pivotally displaced to absorb resisted motion. 45
30. In a line composing machine, an elevator operating shaft having a manual operating means secured thereto, a power operating means freely carried by said shaft, and a constantly urging spring pressed detent constraining to 50 join said manual and power means in operative unison but permitting disconnection therebetween in the event of restricted movement of said shaft. 55
